UNITED STATES PATENT OFFICE.

LELAND J. ARMS, OF BERKELEY, CALIFORNIA.

CARTON FOR FOLDED TISSUE PAPER.

Application filed February 20, 1922. Serial No. 537,945.

To all whom it may concern:

Be it known that I, LELAND J. ARMS, a citizen of the United States, and a resident of Berkeley, county of Alameda, and State 5 of California, have invented a new and useful Carton for Folded Tissue Paper, of which the following is a specification.

The present invention relates to improvements in means for packing and dispensing 10 folded tissue papers, such as are commonly used in lavatories. As now used these papers are packed in strips bent upon themselves once or twice and interfolded with each other so as to form a block which is 15 provided with a wrapper or band for holding it together. These blocks are sold in the market and are placed by an attendant into permanent boxes secured to the wall. To place them into the box the attendant 20 has to first unlock and open the latter, which operation not infrequently involves a considerable loss of time. He then removes the wrapper or band which holds the tissue papers together and pulls one end of the 25 lowermost strip through a longitudinal slot in the bottom of the box, whereupon he closes the same. It will be seen that this manner of handling the paper requires a box permanently secured to the wall, and 30 it further necessitates not only the unlocking and opening of the box but also a handling of the paper by an attendant, which for sanitary reasons is considered undesirable.

35 It is the object of my invention to provide a carton for these papers which will serve the purpose of the wrapper as well as of the dispensing box, thereby allowing the papers to be placed into the 40 carton by the manufacturer and to be withdrawn from the same carton by the person using the paper, without necessitating any handling whatever on the part of an attendant.

45 With this object in view I have illustrated the preferred form of my invention in the accompanying drawing, in which Figure 1 shows a pattern for my carton; Figure 2 a vertical cross section through the same after 50 it has been assembled; Figure 3 a perspective view of the same, and Figure 4 a perspective view of a suitable metallic frame for holding the carton. While I have illustrated only the preferred form of my invention, I wish to have it understood that 55 various changes or modifications may be

made within the scope of the claims hereto attached without departing from the spirit of the invention.

My carton (1) is preferably made of the 60 pattern (2) shown in Figure 1, which comprises a strip of paper or fibre board which may be folded along two longitudinal lines (3) and (4) and along four transverse lines (6), (7), (8) and (9), so as to form the 65 top, bottom, front and rear of the box, while suitable flaps (11) and (12) extend from the front and rear ends adapted to be secured to each other in inter-locking relation by means of suitable projections 70 (13) engaging corresponding slots (14). Other flaps (16) extending from the top and bottom members serve to solidify the 75 structure. The bottom piece (17) is provided with a slot (18) which extends throughout the bottom member and a short distance into the flaps (16) so as to form semi-circular recesses (19) therein. Corresponding recesses (21) are provided in the flaps (11).

For securing the carton to the wall a simple expedient is provided in the slot (22) in the rear side of the carton which may be slipped over a clip (23) fastened permanently to the wall. To prevent the latter 85 clip from engaging the papers within the carton, I provide a cover (24) for the slot which is bent inwardly in its central portion so as to allow the clip (23) to enter between the wall of the carton and the 90 cover for the slot.

If a more elaborate structure is desired for holding my carton, the frame (26) illustrated in Figure 4 may be used. The 95 particular construction of the latter is of little importance, but it should be provided with a slot (27) in its bottom corresponding with the slot in the carton, and it should also have the semi-circular recesses (28) registering with the recesses (19) in 100 the sides of the carton. The frame may be secured permanently to the wall by means of suitable clips (29) and should be provided with recesses (30) in its sides for facilitating the removal of the carton.

105 The operation of the device will be easily understood from the foregoing description. The folded tissue paper strips are placed into the carton by the manufacturer in interfolded relation, and are sold to the customer in the same form and placed by the latter either on the clip (23) or into the 110

frame (26). The removal of the first strip of paper is facilitated by the recesses (19) since they enable the operator to get hold of the lowermost strip with his thumb and one of his fingers. The first strip being in interfolded relation with the second one, a portion of the latter will be pulled through the slot by the removal of the former. Where the frame (26) is used I preferably 10 employ a guiding flange (31) for preventing the strip extending through the slot from pointing towards the wall, which might render its handling more difficult.

I claim:

In combination, means for packing and 15 dispensing interfolded tissue toilet papers comprising a carton having a slot therein through which the papers may be withdrawn successively, transverse extensions of the slot for facilitating the starting of 20 the first strip of paper, and a permanent protective frame adapted to slidably receive the carton having a corresponding slot and corresponding extensions for the same.

LELAND J. ARMS.
